WALLPAPER PASTING MACHINE

Harry A. Bixby, Brattleboro, Vt.

Application April 28, 1950, Serial No. 158,760

4 Claims. (Cl. 118—246)

1

This invention comprises novel and useful improvements in a wallpaper pasting machine, more specifically pertains to a device for expeditiously and conveniently applying paste to pieces or rolls of wallpaper as desired, and constitutes an improvement and a continuation-in-part of my copending application, Serial No. 2,693, filed January 16, 1948, and now matured into Patent No. 2,512,221, issued June 20, 1950.

The principal object of this invention is to provide an improved wallpaper pasting machine of the character and general type set forth in my above identified copending application, but wherein the quantity of paste applied to wallpaper and the like may be accurately controlled.

A further important object of the invention is to provide a wallpaper pasting machine in which the paste applying roller may have excess paste, beyond a predetermined quantity, expeditiously and conveniently removed therefrom.

A very important feature of the invention resides in the provision of an apparatus providing a combined paste receptacle and paste applying roller journaled therein, together with a surplus paste removing roller having an advantageous and novel coaction with the paste applying roller.

These, together with various ancillary objects and features of the invention, which will later become apparent as the following description proceeds, are attained by the present invention, a preferred embodiment of which has been illustrated, by way of example only, in the accompanying drawings, wherein:

Figure 1 is a perspective view, parts being broken away, of a preferred embodiment of the invention;

Figure 2 is a top plan view of the embodiment illustrated in Figure 1;

Figure 3 is a vertical longitudinal sectional view thru the invention; and

Figure 4 is a vertical transverse sectional view taken substantially upon the plane of the section line 4—4 of Figure 3, and illustrating in dotted lines the position of a piece or sheet of wallpaper in proper position on the apparatus for pasting.

The embodiment of the invention disclosed hereinafter and in the accompanying drawings, includes the identical apparatus set forth in my above identified copending application. The same numerals have been applied to the present drawings and description as have been employed in my copending application, and like numerals designate similar parts throughout the various views.

The numeral 10 designates an open-ended casing of any suitable size, shape and material but preferably of sufficient dimensions to receive standard sizes of wallpaper therein. The receptacle 10 is provided with front and rear side walls

12 and 14, together with end walls 16 and 18, the upper end of the receptacle being open as above mentioned.

Extending through and between the front and rear walls 12 and 14 and preferably adjacent one of the end walls, such as 16, is a pivot pin 20 preferably positioned above the level of paste to be contained within the receptacle, for pivotally supporting thereon a frame containing the various parts of the pasting apparatus. This pivot pin may comprise a bolt or shaft extending entirely through the side walls 12 and 14, but in some instances may consist merely of stub axles carried by the front and rear walls and extending inwardly therefrom. In any event, the pin 20 constitutes a hinge or axle about which an end member 24 of the frame is hinged for pivotal movement, as by journals or brackets 26.

The other end member of the frame consists of an end plate 28 provided with a horizontally and inwardly disposed shoulder portion 30 which is adapted to selectively engage and rest upon a support or pin 22 appropriately positioned in the receptacle.

Although the pins 20 and 22 have been shown as separately applied to and extending entirely through the walls 12 and 14 of the receptacle 10, it will be readily understood that they may alternatively consist of integral inward extensions from these walls.

As shown best in Figures 1 and 4, the end plates 24 and 28 are provided with aligned depending lugs or portions 36 and 38 respectively, which preferably terminate just above the normal level of the paste within the receptacle, for a purpose to be later set forth.

As shown best in Figures 1, 3 and 4, a U-shaped support bracket consisting of upstanding legs 40 and 44 connected by a horizontally disposed back portion 42 is provided, the latter preferably being rigidly secured upon the bottom portion or bottom wall of the receptacle. The upper extremities of the legs 40 and 44 are provided with bifurcations 46 and 48 for a purpose to be later set forth, these legs extending upwardly between the end plates 24 and 28 of the frame. The above mentioned depending lugs or brackets 36 and 38 have secured therebetween parallel guide rods or members 50 and 52 at opposite sides of the frame.

These guide rods 50 and 52 are preferably composed of bolts or the like having nuts 54 and 56 on the screw-threaded extremities of one end thereof. By means of these nuts, the end members of the frame may be tightly and rigidly secured together to form a rigid assembly which is pivotal about the pin 20. Extending inwardly from the leg members 40 and 44 of the U-shaped member are a pair of aligned stub axles 58 and 60 upon which parts is journaled a pasting roll

62 of any suitable material which, as shown in Figure 4, is preferably positioned with its lower surface just above the bottom of the receptacle and with its upper surface above the normal level of liquid within the receptacle.

In my above identified copending application, this roll was preferably provided with a plurality of longitudinally extending grooves, and which constituted means for conveying and retaining paste and applying the same to the surface of a paper with which the roll comes in contact. In the present instance, however, it is preferred, although not absolutely essential to the features of this invention, to form the roll 62 of a smooth, cylindrical shape, as clearly illustrated in Figures 1 and 4 of the drawings.

Rigidly secured between the upper ends of the end plates 24 and 28 is a longitudinally and centrally disposed support rod 66, which is adapted to be received within the bifurcations 46 and 48 when the frame is in its lowered position as shown in Figure 3. This support rod or element 66 thus serves to assist in properly positioning the frame when in its lowered position and ready for operation, and serves a further purpose as set forth hereinafter.

As shown best in Figure 2, a plurality of longitudinally spaced studs 68 are screw-threaded through the rear wall 14 into the interior of the receptacle at a suitable position above the level of the liquid therein, as shown in Figure 4. These studs constitute a support means for a sheet or roll of paper as the latter is threaded into and positioned in the device for pasting thereby.

The apparatus as so far described is exactly identical with that set forth and disclosed in my above identified copending application, except that the roll 62 is of a smooth cylindrical shape instead of being grooved.

The present invention envisions improvement upon this previously disclosed apparatus by means of which the amount of paste retained upon the roll for application to the sheet or roll of paper may be accurately regulated, and wherein surplus paste may be wiped from the roll and returned into the paste receptacle therein.

Pivoted to the upstanding legs 40 and 44, as by pivot pins 70 and 72, are a pair of supporting arms 74 and 76, which, at their lower ends, are connected by a transverse shaft 78, upon which is rotatably journaled a roller 80. As will be readily apparent, the shaft 78 and the arms 74 and 76 may be integral so as to constitute a U-shaped member, or if desired the ends of the members 74 and 76 may constitute stub axles upon which and between which the roller 80 is journaled. In any event, it is intended that the roller 80 shall be rotatably mounted so that the same may revolve either in contact with or in fixed slightly spaced relation with respect to the cylindrical surface of the roller 62 during rotation of the latter in order to wipe or remove surplus paste therefrom.

In some instances, it may be found satisfactory to let the roller 80 rest upon the convex surface of the cylindrical roller 62 throughout the entire length of either of these members.

However, it is deemed preferable to provide means for spacing the roller 80 from the surface of the roller 62 by a predetermined distance, and such means may conveniently comprise sleeves, collars or bushings 82 and 84, which may be suitably carried by the roller 80 at predetermined positions thereon. In some instances, it

may be found desirable to form the collars or spacer sleeves 82 and 84 as integral extensions or projections of the roller 80; while in other instances it may be found desirable to form the members 82 and 84 as separate elements which are mechanically applied to and attached to the roller 80. In the latter instance, it will be seen that various sizes of spacer sleeves or rollers 82 and 84 may be applied as desired in order to vary the spacing of the roller 80 from the surface of the roller 62, with the intent that this space shall determine the quantity of paste to be permitted to remain upon the roller 62 and be applied by that roller to the wallpaper as will be apparent from Figure 4. Of course, excess paste will be removed from the roller 62 by the wiping action of the roller 80.

From the foregoing, it will be apparent that the apparatus functions in identically the same manner as that set forth in my previously mentioned copending application, except for the addition of the means for regulating the thickness of paste applied to the roller 62; and for removing surplus paste therefrom, this latter means functioning independently of the rest of the device in order to apply the desired quantity of paste to the paper in an even and uniform film thereon. As will be readily understood, the excess paste removed from the roller 62 by the roller 80 will drop down into the receptacle as shown in Figure 4.

The operation of the apparatus is as follows:

The frame, including the three members 50, 52, and 66, is raised by pivotal movement of the frame about the hinging pin 20, whereby the other end of the frame 28 is elevated above the support rod 22 and above the open portion of the receptacle 10. A sheet or end of the roll of paper as indicated in dotted lines in Figure 4 is now applied to the device. For this purpose, the end of the paper is drawn over the side 12, beneath the two raised guide rods 50 and 52, and above the upper surface of the pasting roll 62, thence upwardly above the surplus paste removing roll 80, and thence upwardly as indicated by the arrow and over the upper support member 66 and then drawn outwardly over the front wall 12. When the paper has been disposed beneath the two guide rods 50 and 52, the end of the same is adapted to rest upon the support studs 68, whereupon the frame is lowered into the receptacle with the support rod 66 received in the bifurcations 46 and 48. This depresses the paper slightly about the upper surface of the pasting roll 62 in the position illustrated in Figure 4.

The end of the paper is then grasped by inserting the fingers of the operator between the studs 68 and the paper drawn about the guide member 50 and over the supporting roll 66 as above mentioned. It will thus be seen that the supporting studs prevent the end of the paper from dropping down into the paste when the paper is initially inserted into the device, and it is desired to use the end of the paper and to apply paste thereto.

Since, in customary operation, the paper hanger cuts off a piece of paper the exact size which it is desired to use, it is obvious that there can be no waste permitted when drawing this paper through the machine for applying paste thereto. In the present apparatus, it is possible to employ quite small pieces of paper, since, as the end of the paper is drawn across the pasting roll in initially inserting the paper in the device, the same be-

comes coated with paste and then rests upon the supporting studs, while the guide rods 50 and 52 are lowered into their operative position. The supporting rod 66 not only serves the purpose of lending rigidity to the frame, but also serves to prevent undesirable contact of the pasted upper fold of the paper with other objects, and also prevents the danger of soiling the unpasted side of the wallpaper by accidental contact with the pasting roll.

From the foregoing, the manner of constructing and operating the device and the advantages arising therefrom will be readily understood. Since numerous modifications and changes will readily occur to those skilled in the art after a consideration of the foregoing specification and attached drawings, it is not intended to limit the invention to the exact construction shown and described, but all suitable modifications and equivalents may be resorted to, falling within the scope of the appended claims.

Having thus disclosed and described the invention, what is claimed as new is as follows:

1. A wallpaper pasting machine comprising an elongated paste receptacle having side and end walls and an open top, a pivot pin positioned transversely of said receptacle and secured between said side walls adjacent one end thereof, an elongated frame hinged at one end on said pin within said receptacle, a support in said receptacle at the other end thereof, said frame resting on said support, a support bracket mounted within said frame and including upstanding arms having bifurcated upper ends, a paste applying roll journaled in said upstanding arms and extending longitudinally of said receptacle between the ends of said frame, paper guide bars depending from said frame on opposite sides of said paste roll, a wiper roll journaled on said upstanding arms and freely rotatable in predetermined spaced relation to said paste applying roll, said frame including first and second end plates and a central support rod joining said end plates, said central support rod seating between the furcations of said arms.

2. A wallpaper pasting machine comprising an elongated paste receptacle having side and end walls and an open top, a pivot pin positioned transversely of said receptacle and secured between said side walls adjacent one end thereof, an elongated frame hinged at one end on said pin within said receptacle, a support in said receptacle at the other end thereof, said frame resting on said support, a support bracket mounted within said frame and including upstanding arms having bifurcated upper ends, a paste applying roll journaled in said upstanding arms and extending longitudinally of said receptacle between the ends of said frame, paper guide bars depending from said frame on opposite sides of said paste roll, a wiper roll journaled on said upstanding arms and freely rotatable in predetermined spaced relation to said paste applying roll, said frame including first and second end plates and a central support rod joining said end plates, said central support rod seating between the furcations of said arms, said first end plate being pivotally secured to said pivot pin, said second end plate resting on said support, guide rods extending between said end plates and flanking said paste applying roller.

3. A wallpaper pasting machine comprising an elongated paste receptacle having side and end walls and an open top, a pivot pin positioned

transversely of said receptacle and secured between said side walls adjacent one end thereof, an elongated frame hinged at one end on said pin within said receptacle, a support in said receptacle at the other end thereof, said frame resting on said support, a support bracket mounted within said frame and including upstanding arms having bifurcated upper ends, a paste applying roll journaled in said upstanding arms and extending longitudinally of said receptacle between the ends of said frame, paper guide bars depending from said frame on opposite sides of said paste roll, a wiper roll journaled on said upstanding arms and freely rotatable in predetermined spaced relation to said paste applying roll, said frame including first and second end plates and a central support rod joining said end plates, said central support rod seating between the furcations of said arms, said first end plate being pivotally secured to said pivot pin, said second end plate resting on said support, guide rods extending between said end plates and flanking said paste applying roller, said wiper roll having its axis parallel to the axis of said paste roll, spacer rolls carried by said wiper roll and engaging the surface of said paste roll.

4. A wallpaper pasting machine comprising an elongated paste receptacle having side and end walls and an open top, a pivot pin positioned transversely of said receptacle and secured between said side walls adjacent one end thereof, an elongated frame hinged at one end on said pin within said receptacle, a support in said receptacle at the other end thereof, said frame resting on said support, a support bracket mounted within said frame and including upstanding arms having bifurcated upper ends, a paste applying roll journaled in said upstanding arms and extending longitudinally of said receptacle between the ends of said frame, paper guide bars depending from said frame on opposite sides of said paste roll, a wiper roll journaled on said upstanding arms and freely rotatable in predetermined spaced relation to said paste applying roll, said frame including first and second end plates and a central support rod joining said end plates, said central support rod seating between the furcations of said arms, said first end plate being pivotally secured to said pivot pin, said second end plate resting on said support, guide rods extending between said end plates and flanking said paste applying roller, said wiper roll having its axis parallel to the axis of said paste roll, spacer rolls carried by said wiper roll and engaging the surface of said paste roll, support arms pivoted to said upstanding arms for vertical swinging movement, said wiper roll being rotatably supported by and between said support arms.
